UNITED STATES PATENT OFFICE.

BARTON S. SNOW, OF BATAVIA, ILLINOIS, ASSIGNOR TO T. W. SNOW CONSTRUCTION CO., OF CHICAGO, ILLINOIS, A CORPORATION OF ILLINOIS.

MATERIAL-HANDLING APPARATUS.

Application filed November 24, 1922. Serial No. 603,009.

To all whom it may concern:

Be it known that I, BARTON S. SNOW, a citizen of the United States, residing at Batavia, in the county of Kane and State of Illinois, have invented a new and useful Improvement in Material-Handling Apparatus, of which the following is a specification.

My invention, as to one phase thereof, relates to material-handling apparatus of the type wherein the material is operated on intermittently to move it from one location to another, as in the case of apparatus employing hoisting buckets supported to reciprocate in an upwardly-extending path, as distinguished from continually receiving and moving the material as would be the case with an endless conveyor. In apparatus operating on the principle first above stated, the load imposed upon the power device which operates the apparatus, is non-uniform, the work to be done by the power device being greater in the movement of the bucket in one direction than in the other.

One of the objects of my invention and which applies to the phase of the invention above referred to, is to provide mechanism for moving the material from one point to another, from which latter point the material is moved, more particularly elevated, by other mechanism to another point, which mechanism shall be operated by a common power device and in such a manner that undue loading of the power device shall be avoided; a further object being to accomplish this purpose by mechanism which shall be simple and economical of construction and positive in operation.

Another phase of my invention relates particularly to the disposal of ashes which are discharged from locomotives in the dumping of their fire boxes. Heretofore it has been the common practice in dumping the fire-boxes of locomotives to dump them over a pit in which the hot ashes, including large masses of burning fuel, are "wet down" to reduce them to the desired low temperature for handling, thus requiring that the ashes be handled in wet condition, entailing the necessity for employing much greater power for actuating the handling apparatus, than would be necessary were the ashes handled in dry condition.

Another of my objects, and one which relates to the phase of the invention just referred to, is to provide for the satisfactory

handling of material dumped from the fire-boxes, without wetting it down.

Referring to the accompanying drawings: Figure 1 is a broken plan view of material-handling apparatus embodying my improvements, the apparatus shown being intended for the handling of the material dumped from fire boxes of locomotives in the cleaning out of the same. Figure 2 is a section taken at the line 2-2 on Fig. 1 and viewed in the direction of the arrows, certain of the parts therein shown being represented diagrammatically. Figure 3 is a broken plan view of the conveyor mechanism forming a part of the apparatus of the preceding figures. Figure 4 is a section taken at the line 4-4 on Fig. 3 and viewed in the direction of the arrows. Figure 5 is a section taken at the line 5-5 on Fig. 3 and viewed in the direction of the arrow. Figure 6 is a section taken at the line 6-6 on Fig. 1 and viewed in the direction of the arrows. Figure 7 is a section taken at the line 7-7 on Fig. 1 and viewed in the direction of the arrows. Figure 8 is a view in end elevation of the shaft of the drum forming a part of the hoisting mechanism, showing a detail of the mechanism by which the conveyor of Figs. 3, 4 and 5 is operated from the power device which actuates the bucket mechanism. Figure 9 is a section taken at the line 9-9 on Fig. 8 and viewed in the direction of the arrows. Figure 10 is a view in elevation of the framework forming the superstructure of the apparatus as is common in material-elevating apparatus of the type employing a reciprocating bucket; and Figure 11, a section taken at the line 11-11 on Fig. 10 and viewed in the direction of the arrows.

In accordance with the particular illustrated embodiment of my invention I provide beneath the track represented at 12 and upon which the locomotives to be dumped run, a long narrow pit 13, the bottom wall thereof, represented at 14, inclining in a direction crosswise of the pit to an outlet 15 in a wall of this pit, this outlet preferably extending continuously for a relatively great length, as, for example, seventy-five feet, the bottom wall of this outlet being shown as formed of a member 16 which forms a continuation of the bottom 14 of the pit 13. The outlet 15 opens into a supplementary pit 17, the bottom of which extends in a plane

below the lower edge of the plate portion 16, as shown in Fig. 7, the pit 17 containing conveying means adapted to receive the material discharging from the pit 13 through its outlet 15 and convey the material to a hopper 18 located at one end of the pit 17, the upper end of the hopper 18 preferably extending below the portion of the bottom wall of the pit 17 which extends adjacent to the outlet 15. The hopper 18, the inclined bottom of which is represented at 19, opens at its outlet 20 into a chute section 21 positioned in one of the side walls of a bucket-receiving pit 22, the bottom of which latter is shown as located below the bottom of the hopper 18.

The conveyor means above referred to may be of any desirable construction, that shown being of the endless type and supported on rotatable members, as for example sprockets represented diagrammatically at 23 and 24, the power for driving the conveyor being communicated to the shaft 25 of the sprocket 24 in a manner hereinafter described. The conveyor shown is formed at opposite sides of series of plates 26 of angle shape in cross-section with their ends overlapped and pivotally connected together as through the medium of the pivoting devices shown at 27, these pivoting devices being provided at their outer ends with rollers 28 journaled thereon, and into the spaces between which the teeth of the sprockets 23 and 24 extend. Spanning the space between the plates 26 at the opposite sides of the conveyor are crosswise-extending plates 29 the opposed edges of which are deflected in opposite directions, as represented at 30 and 31, at which portions they underlap and overlap, respectively, the plates 29 adjacent thereto, as shown more particularly in Figs. 3 and 4. The conveyor structure also involves a framework 32 located in the pit 17 and provided with upper and lower tracks 33 and 34 forming supports for the rollers 28, the tracks being preferably so shaped as to cause the conveyor proper to travel in the path represented by dotted lines in Fig. 2, there being provided above the conveyor proper a rotatable member 35 which operates to cause the upper stretch of the conveyor proper to assume the position shown in Fig. 2.

In the particular construction shown, the material received in the pit 13 in discharging upon the conveyor described, and thence into the hopper 18, is caused to be elevated from this hopper to the desired height, as, for example, for discharge into cars in which it is transported to another location. To this end the apparatus also comprises bucket mechanism which receives the material from the hopper 18 and lifts it to the desired height at which the bucket is dumped. The bucket mechanism shown, which in general

may be the same as that commonly provided in installations of this character, comprises a bucket 36 operating in the pit 22 and connected with one end of a cable 37 which extends upwardly therefrom and over a pulley 70 (not shown) journaled at the upper end of the framework superstructure, represented generally at 39, the other end of this cable being shown as connected with a hoist drum hereinafter referred to. The bucket 36, in accordance with common practice, is so mounted on a bail-like member 41, to which the cable 37 is connected, that the bucket may tilt thereon, the bucket being of such form that it tends to tilt to the right in Fig. 6. The frame 41 is guidingly confined at rollers 42 thereon in vertical guides 43 forming a part of the superstructure 39, the bucket being held against tilting on the frame 41 during the lowering and raising of the bucket, by rollers 44 at opposite sides of the bucket and engaging a vertical guide 45 which latter, in accordance with common practice, may reach short of the upper end of the path of vertical movement of the bucket, whereby the bucket will be caused to automatically dump, by tilting to the right in Fig. 6, upon reaching its uppermost position, for discharge of the material therefrom, as, for example, to a chute 46 which may lead to any desirable point of delivery, as, for example, into a bunker 46^a located above a car into which the elevated material is to be dumped. The apparatus also comprises a counterweight 40 shown as engaging vertical guides 47 formed as a part of the superstructure 39, the counterweight, which moves reversely to the movement of the bucket, being connected with one end of a cable 40^a which extends over a pulley 38 journaled in the framework 39, the other end of the cable 40^a being connected with the hoist-drum referred to.

The chute 21 is shown as provided with a gate 48 formed of side walls 49 extending at opposite sides of the chute 21 and at which the gate is pivoted to the chute, as by the shaft 50, the apron also comprising a crosswise-extending plate-portion 51 which, when the apron is in the position shown in Fig. 6, forms a continuation of the chute and when the apron is swung upwardly to the left in this figure forms a closure for the outer end of the chute. The apron, in the construction shown, is automatically opened and closed responsive to the action of the bucket, by the action of the bucket itself. To this end the apron 48 is provided with depending links 52 arranged at opposite sides of the bucket 36, these links being pivotally connected at their upper ends, as indicated at 53, which the outer ends of the side plates 49 and at their lower ends by a cross-bar 54 which extends into the path of downward movement of the bucket, 130

When the apron 48 is in position for closing the chute 21, in which position it is held by weighting the apron as indicated at 55, the cross-bar 54 extends into the path of downward movement of the bucket 36, and the latter in lowering to the position shown in Fig. 6 turns the apron 48 to the position shown in this figure to permit the contents of the hopper 18 to dump into the bucket, 5 the plate portion 51 of the apron 48 in this position of the latter, extending across the adjacent upper edge of the bucket, whereby when the bucket is elevated the apron 48 will be swung upwardly to return it to the 10 position in which it closes the hopper 18.

The conveyor and the bucket are operated from a power device common thereto and, according to the construction shown, of common form as to its general features of construction. The power device referred to is shown as formed of a drum 56 provided about its periphery with a spiral groove in which the cable 37 is wound. In practice and in accordance with common construction, the cables 37 and 40^a connected with the hoist drum as stated, extend upwardly therefrom whereby as one cable unwinds from the drum in the rotation of the latter in one direction, the other cable winds into the portion of the groove vacated by the unwinding cable. The drum 56, shown as operated by a motor 57, is, in accordance with common practice, rotated first in one direction and then in the opposite direction for raising the 25 loaded bucket from the position shown in Fig. 6 to its uppermost, dumping position, and thereafter to the loading position shown in this figure. The particular mechanism by which the reversing operations are effected, is not illustrated, as such is commonly known in the art. By way of example, however, it may be stated that these reversal operations may be effected by the motor 57 being of the reversible type and 30 associated with any suitable form of current-reversing means.

By preference the counterweight 40 is of such weight as to substantially counterbalance the bucket 36 when the latter is empty, 35 consequently the greatest load imposed on the hoisting mechanism occurs during the elevating of the bucket in filled position. In such an arrangement it is intended that the conveyor operating in the pit 17 be actuated only in alternation with the lifting movements of the bucket, it being preferred that the parts be so proportioned and arranged that practically the same power required for lifting the bucket 36 is required to be expended in operating the conveyor in the pit 17 for moving material to the hopper 18. The mechanism shown for thus driving the conveyor comprises a pawl 58 pivoted, as 40 represented at 59, on a disk 60 secured to the outer end of the shaft 61 to which the drum

56 is connected, this pawl cooperating with a ratchet 62 provided on a sprocket 63 journaled on the outer end of the shaft 61 and shown as connected, through the medium of a sprocket chain 64, with a sprocket 65 secured to the shaft 25. The pawl 58, which is held yieldingly against the periphery of the ratchet 62, by means of a spring 66 carried by the plate 60, is a one-way-operating pawl and serves to actuate the sprocket 63 only when the shaft 61 is being rotated in clockwise direction in Fig. 8, or, in other words, in the direction in which the hoisting drum 56 rotates in the lowering of the bucket 36. 80

Furthermore, as the parts of the construction are proportioned as shown, and as they are, by preference, provided, each operation of the conveyor in the pit 17 delivers to the hopper 18 a quantity of the material sufficient only to form a charge for the bucket 36, so that in each bucket-filling operation the hopper 18 is fully discharged of the material previously introduced therein. 85

Referring now to the use of the apparatus in the disposal of ashes from locomotives, as is well understood by those familiar with this operation, much of the material dumped from the locomotive fire-boxes is in highly heated condition and of a more or less molten condition, and by dumping it into a comparatively long shallow pit, as in the case of the pit 13, it quickly cools and such of the mass thereof as becomes solidified is broken up, by an attendant, for ready discharge through the outlet 15 of the pit, the ashes being subject to still further cooling in their travel from the pit 13 to the bucket 36. The result is that the ashes may be handled in dry condition, in a very economical manner. 100

While I have illustrated and described a particular construction embodying my invention, I do not wish to be understood as intending to limit it thereto as the same may be variously modified and altered without departing from the spirit of my invention. 110

What I claim as new, and desire to secure by Letters Patent, is:

1. In material-moving apparatus, the combination of a member by which the material is moved and which is movable alternately in opposite directions and requires for its movement in one direction the application of power thereto, means for applying power to said member to move the latter, and means for delivering material to said member comprising a movable element and mechanism for driving said element from said first-named means alternately with the application of power to said member as stated. 115

2. In material-moving apparatus, the combination of a member by which the material is moved and which is movable

- alternately in opposite directions, means for operating said member, and means for delivering material to said member comprising a movable element and mechanism for driving said element from said first-named means during the operation of the latter only while driving said member in a direction opposite that for conveying the material.
3. In material-moving apparatus, the combination of a member by which the material is moved and which is movable alternately in opposite directions and requires for its movement in one direction the application of power thereto, means for applying power to said member alternating in its direction of movement, and means for delivering material to said member comprising a movable element and mechanism for driving said element from said first-named means alternately with the application of force to said member as stated.
4. In material-moving apparatus, the combination of a member by which the material is moved and which is movable alternately in opposite directions, means for operating said member alternating in its direction of movement, and means for delivering material to said member comprising a movable element and mechanism for driving said element from said first-named means during the operation of the latter only while driving said member in a direction opposite that for conveying the material.
5. In material-moving apparatus, the combination of material-moving means involving an element which alternates in its direction of movement, and means for delivering material to said first-named means comprising a movable element and mechanism for driving said movable element from said first-named element during the operation of the latter in one direction only.
6. In material-moving apparatus, the combination of hoisting mechanism including a bucket, means for operating said mechanism, and means for delivering material to said bucket comprising a movable element and mechanism for driving said element from said first-named means only during the operation of the latter in operating said first-named mechanism in one direction.
7. In material-moving apparatus, the combination of a hoisting bucket, means for operating said bucket, and means for delivering material to said bucket comprising a movable element and mechanism for driving said element from said first-named means only during the lowering of the bucket.
8. In material-moving apparatus, the combination of material hoisting mechanism comprising a hoisting bucket and a counterweight therefor, said bucket requiring for its movement in one direction the application of

power to said mechanism, means for actuating said bucket, means for delivering material to said bucket comprising a movable element, and mechanism for driving said element from said first-named means alternately with the application of power to said first-referred-to mechanism, as stated.

9. In material-moving apparatus, the combination of hoisting mechanism comprising a hoisting bucket and a counterweight of such size that it requires application of power to said mechanism for raising the bucket when loaded, means for applying power to said mechanism to raise the loaded bucket, and means for delivering material to said bucket comprising a movable element and mechanism for driving said element from said first-named means in alternating with the operation of said first-named means in the raising of the loaded bucket.

10. In material-moving apparatus, the combination of a member by which the material is moved and which is movable alternately in opposite directions and requires for its movement in one direction the application of power thereto, a hoisting device driven in opposite directions alternately and in its movement in one direction applying power to said member, and means for delivering material to said member comprising a movable element and mechanism for driving said element from said hoisting device during the movement of the latter in a direction opposite to its movement last referred to.

11. In material-moving apparatus, the combination of material-moving means involving an element which alternates in its direction of movement, means for delivering material to said first-named means comprising an element movable in one direction, and means for driving said last-referred-to element intermittently from said first-named element during the operations of the latter in one direction only.

12. In a material-handling apparatus, the combination of a pit having an outlet, a hopper, substantially horizontally disposed conveying means arranged to receive the material discharged from said pit through said outlet and convey them to said hopper, means operating to intermittently receive material from said hopper, and means for intermittently operating said conveying means in timed relation to said last-named means to charge said hopper with an amount of material sufficient only to charge said second-named means.

13. In material-moving apparatus, the combination of a member by which the material is moved and which is movable alternately in opposite directions and requires for its movement in one direction the application of power thereto, means for applying power to said member to move the latter,

- and means for delivering material to said member comprising a movable element and mechanism for driving said element from said first-named means alternately with the application of power to said member as stated and substantially throughout the period during which no power is applied, by said first-named means, to said member.
14. In material-moving apparatus, the combination of a member by which the material is moved and which is movable alternately in opposite directions and requires for its movement in one direction the application of power thereto, means for applying power to said member to move the latter, and means for delivering material to said member comprising a collecting member, a device for feeding the material to said collecting member, and mechanism for driving said element from said first-named means alternately with the application of power to said member as stated.
15. In material-moving apparatus, the combination of a member by which the material is moved and which is movable alternately in opposite directions and requires for its movement in one direction the application of power thereto, means for applying power to said member to move the latter, and means for delivering material to said member comprising a collecting member, a device for feeding the material to said collecting member, and mechanism for driving said element from said first-named means alternately with the application of power to said member as stated and substantially throughout the period during which no power is applied, by said first-named means, to said member.
16. In material-moving apparatus, the combination of a hoisting bucket, a material-transferring element and means operating to raise said bucket and actuate said element substantially throughout only the period during which said bucket lowers.
17. In material-moving apparatus, the

combination of material hoisting mechanism comprising a hoisting bucket and a counterweight therefor, said bucket requiring for its movement in one direction the application of power to said mechanism, means for actuating said bucket, means for delivering material to said bucket comprising a movable element, and mechanism for driving said element from said first-named means alternately with the application of power to said first-referred-to mechanism, as stated, substantially throughout the period during which no power is applied, by said first-named means, to said bucket.

18. In material-moving apparatus, the combination of hoisting mechanism comprising a hoisting bucket and a counterweight of such size that it requires application of power to said mechanism for raising the bucket when loaded, means for applying power to said mechanism to raise the loaded bucket, and means for delivering material to said bucket comprising a movable element and mechanism for driving said element from said first-named means in alternation with the operation of said first-named means in the raising of the loaded bucket and substantially throughout the period during which the bucket is being lowered.

19. In material-moving apparatus, the combination of a member by which the material is moved and which is movable alternately in opposite directions and requires for its movement in one direction the application of power thereto, a hoisting device driven in opposite directions alternately and in its movement in one direction applying power to said member, and means for delivering material to said member comprising a movable element and mechanism for driving said element from said hoisting device during substantially the entire movement of the latter in a direction opposite to its movement last referred to.

BARTON S. SNOW.
